UNITED STATES PATENT OFFICE.

CHARLES S. BOARDMAN, OF PITTSBURGH, PENNSYLVANIA, ASSIGNOR TO JONES & LAUGHLIN STEEL CORPORATION, OF PITTSBURGH, PENNSYLVANIA, A CORPORATION OF PENNSYLVANIA.

JOIST HANGER.

Application filed March 23, 1926. Serial No. 96,838.

This invention relates particularly to metal hangers for light weight structural beams (such as the "J & L Jr." beam) and so-called "metal lumber" joists, and aims to provide 5 a positioning and supporting means for such beams and joists for connecting them to the girders and headers of a steel structure, which may be readily manufactured by commercial methods and easily installed within 10 out special tools, and which requires no drilling or preparation for the supporting structure or joist to receive it.

Further objects and advantages of the invention will appear from the description of 15 the illustrative embodiments shown in the accompanying drawings, wherein

Fig. 1 is a side view and Fig. 2 an end view of a double hanger for supporting the abutting ends of two joists from an intervening I-beam;

Figs. 3 and 4 are similar views of a single hanger for use with a channel supporting beam or girder;

Fig. 5 is a side view of a double hanger 25 for supporting joists of different depth on opposite sides of the supporting girder; and

Fig. 6 is a plan view of the hanger shown in Fig. 5.

Referring to Figs. 1 and 2, the double hanger illustrated therein comprises a pair 30 of channel bars 10 disposed side by side and connected at their ends by two U-shaped strips 11. The channel bars may be placed across the top flanges of a beam or girder 12 with the straps disposed on opposite sides 35 of the girder and hanging down like stirrups in position to receive and support the adjacent ends of the steel joists 13. The upper ends of the straps are advantageously 40 bent around the top flanges 14 and back against the webs of the channels, and may be riveted or welded thereto in order to make them secure. The top flanges 14 of the channels may advantageously be arranged 45 to extend across the space over the supporting girders 12 in substantially the same plane as the top flanges of the joists 13, thereby serving to maintain a continuous bearing for the floor slab or structure resting 50 upon the joists.

The flanges or legs of the channels are preferably disposed to face outwards, and the lower flanges are sheared or notched at their outer edges to form two prongs 15 as shown

in dotted lines in Fig. 1, which embrace the 55 top flange of the girder and serve to position the hanger thereon similarly to a saddle. These prongs or clips 15 may be bent around under the top flange as shown to secure the hanger in position and clamp it from movement lengthwise of the beam or girder and from tipping movement over the top of the beam or girder.

The single hanger shown in Figs. 3 and 4 is designed for use with a channel beam or 60 girder, and comprises two angle bars 16 with positioning prongs 17 cut from their horizontal flanges to engage the top flange of the channel 18 and a stirrup 19 suspended from the projecting ends of the angle bars 70 to support the end of the steel joist 20. The single hanger may be used with an I-beam support if desired by lengthening the saddle portions of the angle bars 16 to suit the wider top flanges of the I-beam.

The double hanger shown in Fig. 5 comprises angle bars 21 forming the saddle portion, but as it is designed to support a deep joist 22 on one side and a shallower joist 23 on the opposite side of the supporting girder 24, the straps or stirrups 25, 26, are made to 75 correspond to the depth of the vertical webs and width of the flanges of the respective joists. The prongs or clips 27 are stamped out of the metal of the horizontal flanges of 80 the angle bars between their edges and vertical flanges, thereby avoiding interrupting the continuity of the edges and lessening the liability of twisting the angle bars at these points when overloaded.

It is obvious that hangers embodying the invention may be adapted to various types and dimensions of supporting members, and may advantageously be used for supporting joists and beams of various types.

The positioning or saddle prongs may easily be bent to engage under the top flange by means of an ordinary hammer so as to secure the hangers in proper place lengthwise of the support to suit the desired spacing of the joists prior to raising the latter to position in the structure, so that the joists may be permanently set as fast as they are raised to place. The joists need only to be cut to length before being set in place, and this may be done in advance of raising them, either in the shop or on the ground, as may be most convenient.

The invention is not restricted to the particular shapes shown, and may be adapted by change of one or two dimensions only to meet the usual conditions of service. It is not necessary to carry a large stock of odd sizes of hangers because the stirrups may be made in sizes to suit the several sizes of joist and carried on hand ready to be slipped over the ends of the saddle members and secured thereto upon receipt of an order for hangers to suit any special type or size of beam or girder. The saddle members may be readily cut from the angle or channel bar stock in lengths to suit the particular need, and the prongs when used, may likewise be sheared upon receipt of the order from the lower flanges of the saddle members with tools usually available at steel warehouses.

The invention is simple in construction, inexpensive, readily installed, strong and well adapted to the needs of the type of building construction wherein metal joists are used.

I claim the following as my invention:

1. A joist hanger or the like comprising straight saddle members adapted to rest upon and project over the top flange of a supporting beam or girder member and U-shape stirrup members suspended from the projecting ends of said saddle members, said stirrup members connecting said saddle members and forming seats for the ends of adjacent joists on opposite sides of said supporting member.

2. A joist hanger or the like comprising straight saddle members adapted to rest upon and project over the top flange of a supporting beam or girder and stirrup members connecting said saddle members and forming seats for the ends of adjacent joists on opposite sides of said supporting member, the upper ends of said stirrup members being bent to hook over the projecting ends of said saddle members.

3. A joist hanger or the like comprising saddle members having lateral flanges provided with prongs adapted to embrace the top flange of a supporting beam or girder, said saddle members projecting over the beam at their ends and stirrup members connecting said saddle members and forming seats for the ends of adjacent joists on opposite sides of said supporting member, the upper ends of said stirrup members being bent to hook over the projecting ends of said saddle members.

4. A four part joist hanger or the like

comprising two saddle members having lateral flanges provided with prongs short of their ends adapted to embrace the top flange of a supporting beam or girder, and two stirrup members connecting the ends of said saddle members and forming seats for the ends of adjacent joists on opposite sides of said supporting member.

5. A fabricated steel joist hanger or the like comprising spaced bars adapted to rest upon a support with their ends projecting, a stirrup member having a bearing portion and sides adapted to receive the end of a joist, the upper ends of the sides being secured to the projecting ends of said bars, and means associated with said bars for engaging the support to position said hanger thereon.

6. A fabricated steel joist hanger or the like comprising spaced flanged bars adapted to rest upon a support with their ends projecting, a sheet metal stirrup member secured to the projecting ends of said bars, said stirrup member being bent to embrace the end of a joist, and tongues depending from the flanges of said bars for engaging the support to position said hanger thereon.

7. A joist hanger or the like comprising spaced bars having top and bottom flanges connected by webs, the ends of said bars being secured together by metal strips with their ends bent around the top flanges and extending down alongside the webs and their middle portions forming stirrups for supporting the ends of joists disposed on opposite sides of the support, said strips being spaced on said bars to receive the support between them, and anchoring means for retaining said hanger on the support.

8. A joist hanger or the like comprising spaced bars having top and bottom flanges connected by webs, the ends of said bars being secured together by metal strips with their ends bent around the top flanges and extending down alongside the webs and their middle portions forming stirrups for supporting the ends of joists disposed on opposite sides of the support, said strips being spaced on said bars to receive the support between them, and anchoring means formed in the bottom flanges of said bars for retaining said hanger on the support.

In testimony whereof, I have signed my name to this specification.

CHARLES S. BOARDMAN.
